Calvin Page of Sanbornton, New Hampshire
Letters Patent

The Letters referred to in these Letters Patent and making part of the same containing a description in the words of Plaintiff Calvin Page himself of his improvement in the machine for shelling corn.

To all to whom these presents shall come. Be it known that of Calvin Page of Sanbornton in the County of Strafford and State of New Hampshire have invented and improved a machine for shelling corn, to which machine I attach a drawing annexed hereto by which it is described at the same operation. and I do hereby declare that the following is a full and exact description thereof. The frame of the machine may be varied in its form, but that represented in the drawing thereof deposited in the Patent Office, I have found to be a convenient one. The shelling is effected between a cylinder and a vertical rack or gutter which is made moveable, so that it can be forced close to, or made to recede from the cylinder as may be required. The diameter and length of the cylinder, & also the size and length of the other parts of the machine are to be varied according to the power to be applied to it. The cylinder may be made of wood, and in a small machine may be a foot in diameter and two feet in length. Upon this cylinder iron beaters or shells are to be placed, which may consist of bars, or rods of iron half an inch in width and a quarter of an inch in thickness. These are to pass spirally from end to end of the cylinder. Their inclination may be such as to carry each of them about one third of the way round the cylinder. Of these there may be eight or any other convenient number, all being so as to stand out their whole thickness from the surface of the cylinder. To this motion may be given by means of a cog wheel acting upon a pinion on one end of an iron shaft upon which it revolves. The cylinder will answer well when standing horizontally, but it may be a little inclined towards the end from which the cob, are to escape. The spiral form of the beaters however may be made to force them out without this inclination. In front of the cylinder and extending along its front end to end, is a bar of iron, or a strip of wood faced with iron, upon which the ears of corn rest, and which is supported by the action of the beaters. This stands about level with the axis of the cylinder and may be supported in its place in any convenient way. The bar is pressed against the cylinder by the vertical rack or gutter before named. This consists of vertical slats arranged so as to come together by which they are forced together. This force comp-

8076X

piece works upon plates or hinged ring situated below the rest which sustains the corn usually as low down as the under side of the cylinder. The parts of these slats should be covered with sheet iron to prevent their wearing. Against the back of this sack and near its upper edge, lies the worm or springs are made to press and these may be regulated by screws bearing against them, causing the sack to approach towards, or recede from the cylinder.

This whole machine is covered by a hood or canopy by a hopper or feed hole, through which corn to be shelled falls between the cylinder and the sack, from thence the grain passes directly down or between the slats on to a shoe or sloping bottom where there is a fan or winnowing mill operating in the ordinary way. The shaft of the fan which may be turned by a band from a wheel on the axis of the cylinder, opposite to that on which the pinion is placed. The canopy entirely prevents all scattering of the corn whilst in it there are suitable doors or hatches which may be opened to inspect the work and regulate the machine. At that end of the sack towards which the current of the beaters carries the corn there is an opening left for the escape of the cobs which thus fall outside of the machine. The hopper or feed hole being at the opposite end to prevent its being completely shelled before it passes out. I do not claim as my invention any parts of this machine taken separately, nor do I claim the performing of the operations of shelling and cleaning simultaneously, this having been before effected. But what I do claim is the general construction and arrangement of the shelling part, consisting of the cylinder with its spiral beaters, the rest and the vertical sack constructed in this manner and operating upon the principles known before set forth; without regard however to any particular dimensions or materials or to the price from given to the respective parts.
